UNITED STATES PATENT OFFICE.

GEORGE LEWIS PATTERSON AND ISAAC FRANCIS BADEAU, OF NEW YORK, N. Y.,
ASSIGNORS TO ALICE C. PATTERSON, OF NEW YORK, N. Y.

ELECTRICALLY-OPERATED VIBRATOR.

1,145,507.

Specification of Letters Patent.

Patented July 6, 1915.

Application filed September 8, 1911. Serial No. 648,355.

To all whom it may concern:

Be it known that we, GEORGE L. PATTERSON and ISAAC F. BADEAU, citizens of the United States, residing at New York city, county and State of New York, have invented certain new and useful Improvements in Electrically-Operated Vibrators, of which the following is a full, clear, and exact description.

10 Our invention relates to electrically operated vibrators particularly, though not exclusively, adapted for use in electric bells.

The object of the invention is to provide means whereby the connection with the 15 source of electric energy may be maintained for the greater portion of the travel of the vibrating armature, and whereby the said contact is broken substantially at the completion of the power stroke of the armature.

20 A further object is to provide a construction in which the travel of the contact spring through which the electromagnet is energized may be subjected to the least possible deflection, whereby the life of the 25 spring is preserved for a greater period.

A further object is to maintain the electrical connection with the source of energy for a comparatively extended portion of the power stroke of the armature so that the 30 blow, (for example,) delivered by the gong striking arm may be rendered the more powerful.

A further object is to eliminate the energizing of the electric magnets through the 35 frame of the bell.

With these and other objects in view, as will appear from the following description, the invention consists in a construction and arrangement of parts, a preferred embodiment of which is illustrated in the accompanying drawings, in which—

Figure 1 is a plan view of an electric bell embodying our improvements. Fig. 2 is a fragmentary side elevation looking from the right of Fig. 1. Fig. 3 is a fragmentary under side view of the bell frame and magnet connections; and Fig. 4 is a view of a detail of construction looking from above Fig. 1.

50 The embodiment of our invention herein selected for illustration comprises a bell frame 1 on which a bell 2 is mounted by a bolt as at 3.

4—4 indicate the coils of the electromag-

net, the latter having poles 5—5. Opposite the poles is the armature 6 pivoted in any suitable manner as at 7, and having a spring 8 to return the armature to initial position.

Upon the frame 1 are mounted contact posts 9 and 10, in the former of which an adjustable contact screw 11 is mounted and on the latter a spring contact 12. Upon the opposite side of the frame is a contact post 13. The leads from the source of energy are connected to the posts 10 and 13 respectively. The contact posts 10, 11 and 13 are securely mounted on the frame by means of base plates 10', 11' and 13', the screws 10², 11² and 13² said parts being carefully insulated from the frame.

Referring to Fig. 3, showing the under side view of the frame and connections, it will be seen that the post 11 is connected with the electric magnets by means of the screw 11² and a connection 14, while the post 13 is likewise connected with electric magnets by means of the screw 13² and lead 15. The lead 16 connects the coils of the electric magnets.

Upon the armature 6 and insulated therefrom is mounted a loop member 17 by means of a clip 18. As will be seen by referring to Figs. 1, 2 and 4, the contact spring 12 passes through this loop 17. Referring particularly to Fig. 4, in which the armature is shown in the position to which it is moved by the magnetism of the coils and at the end of its power stroke, it will be seen that the opening of the loop 17 is of such depth that the contact spring 12 is moved but a short distance from the contact screw 11, and furthermore, from this construction it will be obvious that the contact spring remains in contact with the screw 11 for the greater portion of the power stroke of the armature, whereby a more powerful blow is delivered by the striker on the gong. Furthermore, by reason of the short travel of the contact spring in breaking connection with the screw 11, the spring is preserved from crystallization, commonly found in bells of this general character wherein the contact spring is mounted upon the armature, and is subject to violent and considerable deflection at each stroke of the armature.

A further advantage of this improved construction is that the reengagement of

the spring with the contact screw is rapid owing to its short travel whereby the rate of vibration is accelerated.

While we have herein shown a return spring 8 for the armature, it is to be understood that this is not essential to the operation of the device, since the action of the contact spring 12 will of itself serve to free the striker from the gong sufficiently to permit vibration under the magnetic action of the magnets 4. In so far as our experiments have shown, it seems conducive to the most efficient operation that a separate return spring, such as 8, be employed.

In one aspect of the invention, however, the return spring may be entirely eliminated.

While we have herein shown and described a particular embodiment of our invention, it is to be understood that the same may be altered in detail and arrangement of parts within the scope of the appended claim.

What we claim is:

In an electric vibrator device, an electro-magnet, relatively movable armature arranged to coöperate therewith, a main

spring separate from said armature and normally tending to move said armature away from said magnet, a contact device including a pair of contact points, one of the same being movable, a blade spring carrying said movable contact point, a rigid mounting for said spring, means carried by said armature and operative, during movement thereof toward said magnet, to make mechanical engagement with said blade spring near said movable contact point but at one side thereof, said means having a limited amount of independent movement relatively to said blade spring, said spring acting as a yielding back stop for said armature, the tension of said blade spring being in a direction to withdraw said armature from said magnet, said blade spring also normally tending to hold said contact points against each other.
